[57] CLAIM

The ornamental design for an ice skate picture frame, as shown and described.

DESCRIPTION

FIG. 1 is a front elevational view of an ice skate picture frame having a textured front surface with raised ridges and a recessed aperture for receiving a picture;

FIG. 2 is a top view of the ice skate picture frame;

FIG. 3 is a bottom view of the ice skate picture frame;
FIG. 4 is a rear elevational view showing the frame support members and the outline of a removable cover for placing and retaining the picture in place within the recessed aperture;

FIG. 5 is a left side elevational view of the ice skate picture frame; and,

FIG. 6 is a right side elevational view of the ice skate picture frame.
